UNITED STATES PATENT OFFICE.

FIRM B. BYERS, OF NEW YORK, N. Y.

SPLICE-BAR OR HOLDER.

1,162,976.

Specification of Letters Patent.

Patented Dec. 7, 1915.

Application filed December 17, 1913. Serial No. 807,248.

To all whom it may concern:

Be it known that I, FIRM B. BYERS, a citizen of the United States, residing at New York, in the county of New York and State of New York, have invented new and useful Improvements in Splice-Bars or Holders, of which the following is a specification.

The present invention is directed to improvements in splice bars or holders for rails, and has for its object to provide a device of this character so constructed that when clamped upon the base flanges of the rail the likelihood of breaking or cracking of the base flanges is eliminated.

15 A further object of the invention is to provide splice bars or holders for application at the meeting ends of rail sections, or immediate the ends thereof, said splice bars being adapted to rest upon a plurality of 20 ties so as to prevent the same from moving toward or away from each other.

A still further object of the invention is to provide a device of this character which will operate with equal success upon sixty 25 foot rails or the conventional thirty foot rail, said device being so constructed as to permit the usual expansion and contraction due to the change of temperature, but at the same time preventing sliding or buckling of 30 the rails usually prevalent due to heavy traffic thereover.

A still further object of the invention is to provide a splice or holder which will impart to the rails the necessary stability.

35 With these and other objects in view, this invention resides in the novel features of construction, formation, combination and arrangement of parts to be hereinafter more fully described, claimed and illustrated in 40 the accompanying drawings, in which:

Figure 1 is a bottom plan view of the device. Fig. 2 is a side elevation. Fig. 3 is an end view. Fig. 4 is a vertical sectional view through the device.

45 Referring to the drawing, the numeral 1 designates the usual rail sections, which comprise the webs and base flanges 2 and 3, respectively, said webs being provided with the usual bolt openings 4, and through 50 which clamping bolts 5 are passed.

The splice bars 6 are provided with apertures 7 which are adapted to register with the bolt openings 4, whereupon the clamping bolts 5 are passed through the registered 55 openings and apertures, thus firmly clamping the splice bars or holders in proper posi-

tion upon the meeting ends of the rails, or intermediate the ends thereof, as the occasion may require.

The splice bars or holders 6 are formed 60 from rolled metal and are stamped with suitable dies so as to provide the lower edge with downwardly and inwardly directed lugs 8, the lower edges of which being disposed below the plane of the flanges 9, said 65 lugs having their opposite ends integrally connected to the adjacent ends of the flanges 9 by angularly shaped tie engaging sections 10 which are downwardly inclined so as to more readily engage the confronting faces 70 of the ties 11.

Formed near the outer end of each bar or holder 6 are tie engaging sections 12, the same being also angularly shaped and are inclined outwardly so as to engage the outer 75 faces of the ties 11.

The sections 12 are integrally connected to the flanges 9 by the plates 13, said plates serving to effectually brace the sections 12.

The flanges 9 are adapted to rest upon the 80 ties 11, and at which time the tie engaging sections 10 and 12 will engage the ties so as to prevent creeping thereof, and at the same time the bars or holders will be held against creeping.

The base flanges 3 of the rails rest upon the flat surfaces 14 of the flanges 9, said surfaces terminating at their outer sides in channels 15, said channels being of dimensions that will permit the outer edges of the 90 base flanges to project thereinto so that a space 16 is formed above the outer edge of the base flange, and a space 17 below the same, thus preventing the initial weight of the traffic from breaking the rail base 95 flanges, as the weight of the traffic will be equalized at the points A, B and C, said points being vertically alined so that the weight of the traffic will be received upon the flanges 9.

When sixty foot rails are in use the bars or holders will not only be clamped at the meeting ends of the rails, but will be placed intermediate thereof, thus permitting the use of such rails, which would spread or 105 buckle if the bars or holders were applied only at the meeting ends, as the sliding movement of a sixty foot rail is greater than that of a thirty foot rail.

What is claimed is:—
110
The combination with a track rail, of splice bars having integral rail base receiv-

ing flanges, the ends of said flanges having formed therewith inwardly directed plates, said plates being connected at their inner edges to the flanges by outwardly inclined 5 triangular sections, inwardly and downwardly directed lugs formed integral with the base flanges intermediate their ends, tie engaging sections connecting the ends of the lugs to the flanges, said tie engaging sec-
10 tions being disposed opposite the first named sections, and being adapted to engage the

confronting sides of a pair of ties when the first named sections engage the outer sides of said pair of ties.

In testimony whereof I have hereunto set 15 my hand in presence of two subscribing witnesses.

FIRM B. BYERS.
